No 2,273.

John D Armstrong.
Design for a Military Burotaph.
Patented March 6, 1866.

D.S. 2273

John L. Armstrong, Bismarck, Minn. His

Letter Patent No. 2273-Dated, March 6, 1866.

Design for a military Cenotaph.

Specified and referred to in these Letters Patent and making part of the same.

To all whom it may concern:

Bent before stated John L. Armstrong of the Town of Bismarck in the County of Brown, in the State of Wisconsin, have invented a new and improved mode of building, designing and erecting Soldier's Cenotaphs, Military Cemetery and State Monuments; and I do hereby declare that the following is a full and exact description thereof, reference being had to the accompanying drawings and to the letter of reference marked thereto:

The nature of my invention consists in erecting and placing four small pedestals or monuments on each side of the main monument, the small pedestals to be made of marble, and mounted with a canon, made of marble, bronze or other suitable material. The pedestals as lettered "a", in the drawings.

What I claim as my invention, and desire to secure by Letters Patent, is, The design for a monument as shown and described.

Witness:

C. B. Thomas, }
